(57) **CLAIM**

The ornamental design for a mobile phone as shown and described.

DESCRIPTION

FIG. 1 is a front view of a mobile phone of the first embodiment showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof;

FIG. 9 is a perspective view thereof with the camera raised;

FIG. 10 is a front view of a mobile phone of the second embodiment showing the new design;

FIG. 11 is a back view thereof;

FIG. 12 is a left side view thereof;

FIG. 13 is a right side view thereof;

FIG. 14 is a top view thereof;

FIG. 15 is a bottom view thereof;

FIG. 16 is a perspective view thereof;

FIG. 17 is another perspective view thereof;

FIG. 18 is a front view of a mobile phone of the third embodiment showing the new design;

FIG. 19 is a back view thereof;

FIG. 20 is a left side view thereof;

FIG. 21 is a right side view thereof;

FIG. 22 is a top view thereof;

FIG. 23 is a bottom view thereof;

FIG. 24 is a perspective view thereof;

FIG. 25 is another perspective view thereof;

FIG. 26 is a perspective view thereof with the camera raised;

FIG. 27 is a front view of a mobile phone of the fourth embodiment showing the new design;

FIG. 28 is a back view thereof;

FIG. 29 is a left side view thereof;

FIG. 30 is a right side view thereof;

FIG. 31 is a top view thereof;

FIG. 32 is a bottom view thereof;

FIG. 33 is a perspective view thereof; and,

FIG. 34 is another perspective view thereof.

(Continued)

The broken lines in the drawings show portions of the mobile phone that form no part of the claimed design in the embodiments in which they are shown.
